US00D952672S

(12) **United States Design Patent** (10) **Patent No.:** **US D952,672 S**
Ashenden et al. (45) **Date of Patent:** **** May 24, 2022**

(54) **DISPLAY SCREEN OR PORTION THEREOF WITH GRAPHICAL USER INTERFACE**

(71) Applicant: **NextNav, LLC**, Sunnyvale, CA (US)

(72) Inventors: **John Ashenden**, San Francisco, CA (US); **Deepak Joseph**, Oakton, VA (US); **Robert Rovetta**, Cupertino, CA (US); **Frank Yenshaw**, San Mateo, CA (US)

(73) Assignee: **NextNav, LLC**, Sunnyvale, CA (US)

(**) Term: **15 Years**

(21) Appl. No.: **29/732,468**

(22) Filed: **Apr. 24, 2020**

Related U.S. Application Data

(63) Continuation of application No. 16/809,487, filed on Mar. 4, 2020, now abandoned.

(51) **LOC (13) Cl.** **14-04**

(52) **U.S. Cl.**

CLAIM

The ornamental design for a display screen or portion thereof with graphical user interface, as shown and described.

DESCRIPTION

The sole FIGURE is a front view of a display screen or portion thereof with graphical user interface showing the claimed design.

The broken lines in the sole FIGURE show portions of the graphical user interface or the display screen that form no part of the claimed design.

1 Claim, 1 Drawing Sheet
